UNITED STATES PATENT OFFICE.

WILLIAM ZEEDKY, OF PATERSON, NEW JERSEY, ASSIGNOR TO BENJAMIN EASTWOOD COMPANY, OF PATERSON, NEW JERSEY, A CORPORATION OF NEW JERSEY.

LOOM.

Application filed May 28, 1921. Serial No. 473,507.

To all whom it may concern:

Be it known that I, WILLIAM ZEEDKY, a citizen of the United States, residing at Paterson, in the county of Passaic and 5 State of New Jersey, have invented certain new and useful Improvements in Looms, of which the following is a specification.

The present invention relates to looms, and it consists in part in certain improvements in shuttle impelling means for looms of the class in which the shuttle-impelling or picking member is spring-pressed and in part in certain improvements in the means for controlling the starting and stopping 15 of the loom.

In the drawings,

Figure 1 is a front elevation of enough of a loom embodying the invention to illustrate the latter;

20 Figure 2 is a right side elevation;

Figures 3 and 4 are a front elevation and a plan, partly in section, of the shuttle impelling means;

25 Figure 5 is a plan of the means for automatically cutting out the shuttle impelling operation when the loom stopping means is operated, and Figure 6 illustrates a detail of the same;

Figure 7 is a front elevation, partly in 30 section, of the means for controlling the starting and stopping;

Figure 8 is a left side elevation of the last-named means showing the various control levers in the position where the power is ap- 35 plied and the brake released;

Figure 9 is a similar view showing said levers shifted to the position where the loom is stopped; and

40 Figures 10 and 11 are views illustrating principally the levers *a* and *b*.

The following parts are or may be substantially the same as corresponding parts in the loom set forth in my application Serial No. 413,321, to wit: The loom sides *a*; 45 the rock-shaft *b* on which the lay-swords *c* for the lay or batten *d* are fixed; each bracket *e* secured on the rock-shaft by having a sleeve portion *e'* thereof fitted over and held by screws thereon, the bracket having an up- 50 standing arm *e²* and an outwardly projecting arm *e³*; each lever *f* fulcrumed on a stud in arm *e²* and having a downwardly projecting arm *f'*, an upwardly projecting arm *f²* (to be more particularly described here- 55 after), and an inwardly projecting arm *f³*;

each cocking shoe *g* fulcrumed on a stud in the outer end of, and normally upheld by a spiral spring *h* resting on, bracket *e*; said shoe having a shoulder *g'* to be engaged by a cocking shoulder formed by the end of arm *f'* of lever *f*; each spring *i* of the laminated plate type arranged on a stud *i'*; each universal joint connection *j* (including the clevises *j'* and *j²* pivoted together and arranged at right angles to each other and one being pivoted to the end of said spring and the other to arm *f³* of lever *f*) between lever *f* and said spring which, under the pressure of the adjusting screw *k* on the loom side, tends to move said lever in the direction to throw the shuttle; and each master lever *l* fulcrumed in the frame side and being adapted to be rocked, as from the crank shaft of the loom, through means (not shown) and in such manner that when its forward end moves down it will depress the cocking shoe to release the (cocked) lever *f* and when it rises it will engage a roller *f⁴* on lever arm *f³* and move the lever back to re-engagement with the cocking shoe, i. e., 70 to cocked position.

The arm *f²*, by having forwardly projecting lugs *f⁵*, forms in effect a crotch in which is arranged a substantially rectangular socket piece *m*, open at the top and front, 85 which has at its lower inner corner a projecting lug *m'* which is fulcrumed on a stud *n* in said arm. The socket piece receives the lower end of the picker stick *o* which snugly fits the same and is secured 90 therein by the screw-bolts *p*. The socket piece and contained picker stick are free to rock on the stud from one lug *f⁵* to the other, which serve as stops to such movement and are spaced apart somewhat more than the 95 socket piece is wide; or one of these stops may be afforded by a set screw, as shown, to permit adjustment. Thus lost-motion is permitted the picking device, constituted by the parts *m* and *o*, in the mounting therefor afforded by lever *f*, so that when on each cocking the entire structure is moved a trifle beyond the actual cocking point in order to insure cocking, said mounting can move 100 back to the cocking point without correspondingly moving back with it the picking device and consequently disturbing the shuttle; this function of the parts is not new, so I make no claim thereto, although the 105 construction shown is new, and it is that 110

which I claim, as will be hereinafter pointed out.

In order, as set forth in my mentioned application, to prevent tripping of the picking members when the power is shut off and the loom is to be "turned over" by hand, I have provided the levers *q* respectively fulcrumed on the brackets *e* to move in horizontal planes over the inner ends of the cocking 10 shoes, the levers being connected by the links *r* with the ends of an intermediate lever *s* fulcrumed on shaft *b* so that their rearward ends move inward and outward together and being adapted to be actuated 15 from the controlling shaft *t* of the loom through a rod *u* and a lever *u'* having a slot receiving the tongue *q'* of one of the levers *q*. Each lever *q* has a bearing *q²* (Fig. 6) in which is vertically movable a button *v* 20 whose lower end rests on the corresponding cocking shoe and wipes over the same when the levers *q* are moved into and out of position to be depressed by the corresponding lever *l* and so depress the cocking shoe. 25 On one end of shaft *t* is fixed a lever *w* which above the shaft has a handle, as shown, and a lug *w'* projecting inwardly from a rearwardly extending arm *w²* and below the shaft a roller *w³*. This roller 30 travels in a cam-slot in a lever *x* which is fulcrumed in the loom side to move in a horizontal plane and controls the suitably driven movable member *y* of a clutch on the crank shaft *z* of the loom; when lever *w* 35 is moved to the full-line position shown in Fig. 8 the roller engages in a notch *x'* in the cam slot of lever *x*, so that the lever becomes locked in the new position and holds the clutch member against the clutch member 40 2, suitably driven and freely revoluble on the shaft *z*, so that the power is on and the loom is driven. In an adjusting slot of arm *w⁴* of lever *w* is pivoted a forwardly projecting pawl *3* having a depending hook 45 or nose at its forward end. Freely oscillative on the shaft *t* is a lever *4* whose hub has an upwardly projecting lug *4^a* to be engaged by pawl *3*. The upper end of this lever is opposed by and engageable with lug *w'* of 50 the other lever and it forms a handle and has an outwardly projecting lug *4^b* positioned so as to be abutted by the pawl *3* in a way to be stated; the lower end of said lever *4* is forked, at *4^c*, and it has a lateral web 55 *4^d* affording an impact face for the dagger 5 of a weft-stop mechanism, the remaining part of which is not shown since it is not material and may be of any usual construction. Said fork *4^c* contains a roller *4^e* and it 60 receives the upwardly projecting end of a brake lever *6* which under the influence of a spring *7* normally tends to hold a band *8* in braking engagement with a brakewheel *9* on the crank shaft; but when lever *4* is moved 65 to the full-line position in Fig. 8 and the roller *4^e* consequently runs along the incline *6^a* of brake-lever *6* and finally falls in a notch *6^b* therein the two levers *4* and *6* are locked in that position, holding the brake released. Lever *6* has an upright set-screw *6^c* 70 which underlies pawl *3*. On the other end of shaft *t* there may be fixed another lever *10*. The backward limit of movement of the lever *w* (Fig. 9) is determined by roller *w³* reaching the forward end of the slot in lever *75* *x*. Spring-pressed lever *6* affords the principal motive power to throw the levers *4* and *w*, once roller *4^e* is made to clear the notch *6^b*. Thus, if lever *4* be pushed back (by hand or by the dagger *5* going into action) 80 sufficiently to clear roller *4^e* from the notch, or if it be pulled back to the same extent by the pawl *3* as the result of the attendant rocking shaft *t* by pushing back on either lever *w* or *10*, said lever at once it is thus tripped 85 will be thrown back violently by brake lever *6* against lug *w'* thus to impel lever *w* to the prescribed limit of backward movement thereof so as to throw off the power, but not before brake-lever *6* has applied the brake 90 to the crank shaft. When the levers move toward their backward positions (Fig. 9) pawl *3* wipes over set screw *6^c*, which rises with brake-lever *6*, and so it becomes cleared from lug *4^a* and takes position behind lug *95* *4^b*. The operator can now move and lock forward the lever *4* alone, since the two levers *w* and *4* are uncoupled, for the purpose of releasing the brake and turning over the loom by hand; and in operating the loom in 100 this way, it will be noted, the picking mechanism will not be actuated because, shaft *t* remaining in the position of Fig. 9, the buttons *v* are withdrawn from between the levers *l* and the cocking shoes. If the loom 105 is to be started again under power the lever *w* is moved to the position of Fig. 8; if the lever *4* is back (Fig. 9), the pawl by abutting lug *4^b* transmits the movement to lever 110 *4*, the pawl falling as soon as the operator relaxes the pressure on lever *w* and thus again clearing lug *4^b*, as in Fig. 8. What I have thus described with respect to the power and brake control means is not new 115 except in so far as it involves the coupling afforded by pawl *3*. That is to say, given a brake actuating member, as *4*, and an actuating member, as *w*, for the power controlling means, such members being movable back and forth substantially parallel with each other, it is new to provide a coupling normally connecting them and adapted to move the first member to the brake-applying position when the second member is moved 120 to position to cut off the power, and means to uncouple the coupling from one member upon their moving to said position, whereby the brake member may thereupon be moved to release the brake independently of the second member. It is also new, given 125

these members and one of them having impact faces, one facing backward and the other forward, to provide a coupling movable on the other member and impingeable 5 against one or the other of said faces and normally held in position to impinge against one of them whereby movement of one member in one direction will be imparted through the coupling to the other member and means 10 to shift the coupling into position to impinge against the other of said faces upon movement being so imparted to said other member, whereby the latter member can then be moved in the other direction independently 15 of or by the other member through said coupling.

Having thus fully described my invention, what I claim as new and desire to secure by Letters Patent is:—

20 1. In combination, a loom frame, braking means including an actuating member movable back and forth to apply and release the brake, power controlling means including an actuating member movable back and forth substantially parallel with the first member to apply and cut off the power, a coupling normally connecting said members and adapted to move the first member to position to apply the brake when the second member moves to position to cut off the

power, and means to uncouple said coupling from one member upon said members moving to said positions, whereby the first member may be thereupon moved to release said brake independently of the second member. 35

2. In combination, a loom frame, braking means including an actuating member movable back and forth to apply and release the brake, power controlling means including an actuating member movable back and forth substantially parallel with the first member to apply and cut off the power, one member having impact faces one facing backward and the other forward, a coupling movable 40 on the other member and impingeable against one or the other of said faces and normally held in position to impinge against one of them whereby movement of one member in one direction will be imparted through the coupling to the other member, and means to shift the coupling into position to impinge against the other of said faces upon movement being so imparted to said other member, whereby the latter member can be 45 moved in the other direction independently of or by the other member through said coupling.

In testimony whereof I affix my signature.

WILLIAM ZEEDYK.
